MUFFLER

James P. Moss, 11001 Knight Road, Grass Lake, Mich.

Filed May 5, 1965, Ser. No. 85,105

Term of patent 14 years

(Cl. D14—6)

FIGURE 1 is a perspective view of a muffler showing my new design;

FIGURE 2 is a fragmentary enlarged perspective view thereof;

FIGURE 3 is a fragmentary side elevational view thereof; and

FIGURE 4 is a transverse cross-sectional view taken along the line 4—4 of FIGURE 3.

The dominant features of my design reside in the portions shown in full lines.

I claim:

The ornamental design for a muffler, substantially as shown and described.
